METHOD OF MAKING TURN-SHOES

1,142,741.

Specification of Letters Patent. Patented June 8, 1915.

Application filed September 8, 1914. Serial No. 860,704.

To all whom it may concern:

Be it known that I, PEARL J. WENTWORTH, a citizen of the United States, residing at Hyde Park, in the county of Norfolk and State of Massachusetts, have invented certain new and useful Improvements in Methods of Making Turn-Shoes; and I do hereby declare the following to be a full, clear, and exact description of the invention, such as will enable others skilled in the art to which it appertains to make and use the same.

The present invention relates to an improved method of making turn shoes and more particularly to improvements in the method of imparting the desired shape to the shoe sole.

In the manufacture of turn shoes as ordinarily practised, the shoes are first lasted and sewed wrong side out, are next removed from the last and turned while in temper, and are finally re-lasted to enable the sole to be beaten out to the shape of the last and the various finishing operations to be properly performed. It will be obvious to those skilled in the art that after the shoe is turned and re-lasted the margins of the sole will stand out from the last and more particularly in shanks having a pronounced transverse curvature, and as the last completely fills the shoe the margins of the sole must be pulled down to the last in order to permit the opposite edges of the vamp to be brought into the proper relation to one another. This causes a considerable strain to be exerted upon the upper when the shoe is re-lasted, and frequently the upper stock is unable to withstand the strain of pulling the margins of the sole into place, causing the upper to stretch and distort the shoe. This is especially true in the case of shoes having high, arched shanks in which a greater transverse curvature is imparted to the sole, and if the sole is later beaten out or leveled by hand or machine to impart the proper transverse curvature, a slack is produced in the upper at the points of greatest strain, which seriously impairs the finished appearance of the shoe. It has been attempted to remedy this condition by molding the sole after the shoe has been turned and partially or wholly dried out, but this method is objectionable as the heavy pressure necessary to mold the sole frequently

breaks the grain of the sole, weakening it, 55 and marring the finished appearance.

The object of the present invention is to provide an improved method of making turn shoes which enables the sole to conform closely to the lines of the last at all points 60 without stretching the upper or otherwise distorting the true lines of the shoe.

With this object in view a feature of the invention consists in making the shoe wrong side out upon a last, turning the shoe off 65 the last, molding the sole of the shoe to the finished shape while the shoe is in temper, and finally re-lasting the shoe.

In the accompanying drawings illustrating the preferred form of apparatus for 70 practising the improved method; Figure 1 represents a section in elevation of the co-operating sole molding forms with a shoe inserted between them at the commencement of the pressing operation; Fig. 2 is a view 75 similar to Fig. 1 showing the forms in a position of pressure with the sole clamped between them and illustrating the manner in which the sole is molded; and Fig. 3 is a side elevation of the forms with the shoe 80 supported between them and illustrating the manner in which the forms bear upon the sole longitudinally.

With the usual methods of manufacture employed the upper 1 is first lasted to the 85 sole 2 in the usual manner and secured by a line of inseam stitches indicated at 3. The shoe is then removed from the last and tempered with water to render the soles flexible and permit the shoe to be turned with 90 facility.

It will be obvious to those skilled in the art that the initial transverse curvature of the sole is the reverse of that in the finished shoe and in the ordinary method of manufacture the sole is shaped to approximately the final curvature by placing the shoe upon the last after the turning operation has been completed and drawing the opposite edges of the upper together to pull the margins of 100 the sole down to the last. This causes a considerable strain to be exerted upon the upper, frequently stretching it and distorting the true lines of the shoe. According to this method, if the sole is later leveled and the 105 margins finally forced into contact with the last a slack is produced in the upper. In the present invention after the shoe is turned,

2
 and while the sole is still in temper it is positively molded to the desired curvature thus enabling the shoe to be later re-lasted and the upper fastened properly without the necessity of straining upon the upper to pull the sole into place. In the preferred method employed, a stiffening member is inserted in the shoe and the sole is positively molded about the stiffening member between two 10 molds which are designed to engage the sole between them and impart the desired curvature with the stiffening member in position in the shoe. To this end after the shoe has been turned and a shank stiffener 5 inserted, 15 the shoe is placed upon a supporting form 6, and a coöperating pressing form 7 is actuated to engage with the opposite face of the sole and cause the sole to be molded between the two forms, as shown clearly in Fig. 2. 20 It will be observed from an inspection of Fig. 1 that the pressing form 7 first engages with the margins of the sole and as the movement of the pressing form continues toward the supporting form the margins 25 of the sole are pressed downwardly and the entire sole is stretched transversely, the pressing form gradually contacting with an increasing area of the sole until it reaches the pressing position shown in Fig. 2. In 30 order to prevent the breaking of the stitches when the two forms are in pressing position the supporting form 6 is arranged to engage and support the shoe between the two opposite lines of inseam stitches, as shown clearly 35 in Fig. 2, thus avoiding the application of a direct pressure upon the fastenings. By molding the sole in this manner while in temper the proper curvature may be imparted to it without breaking the grain of the sole and, furthermore, the sole is firmly set 40 without any tendency to straighten out during the re-lasting operation.

The operations which are performed as above described and illustrated in the drawing are those which are preferred in practising the present invention but it is to be understood that except as defined in the claims the invention is not limited to the precise method illustrated and described.

45 The invention having been described, what 50 is claimed is:

1. A method of making turned shoes which comprises lasting the shoe wrong side out upon a last, removing the shoe from the last and turning the shoe with the sole in temper, molding the sole of the shoe to the finished shape while the sole is in temper, and finally re-lasting the shoe.

55 2. A method of making turned shoes which comprises making the shoe wrong side out upon a last, removing the shoe from the last and turning the shoe with the sole in temper, inserting a stiffening member and molding the sole to the final shape while the sole 60 is in temper, and finally re-lasting the shoe.

65 3. A method of making turned shoes which comprises lasting the shoe, turning the shoe while off the last and with the sole in temper, applying pressure to the sole in a manner to stretch it transversely and impart the 70 final curvature while the sole is in temper, and finally re-lasting the shoe.

75 4. A method of making turned shoes which comprises lasting and sewing the shoe wrong side out upon a last, turning the shoe while off the last and with the sole in temper, molding the sole while still in temper to the desired curvature by a direct pressure applied between the lines of inseam stitches, and finally re-lasting the shoe.
